[57] CLAIM

The ornamental design for a design of display package for lockset, as shown and described.

DESCRIPTION

FIG. 1 is a front view of a display package for lockset according to the present invention;

FIG. 2 is a right side view of the display package for lockset shown in FIG. 1;

FIG. 3 is a left side view of the display package for lockset shown in FIG. 1;

FIG. 4 is a rear view of the display package for lockset shown in FIG. 1;

FIG. 5 is a bottom view of the display package for lockset shown in FIG. 1; and,

FIG. 6 is a top view of the display package for lockset shown in FIG. 1.

The broken line disclosure is for illustrative purposes only and forms no part of the claimed design.
